FUEL SUPPLY PUMP

William J. Smith and William W. Slaght, Rocky River, Ohio, assignors to Cleveland Steel Products Corporation, Cleveland, Ohio, a corporation of Ohio

Application March 4, 1939, Serial No. 259,901

9 Claims. (Cl. 103—42)

This invention relates to fuel supply pumps and particularly to pressure pumps for use with oil burning apparatus.

One of the objects of the present invention is to provide a fuel supply pump for oil burning apparatus which is compact in its arrangement of parts, simple in construction and arranged to be quickly and easily assembled.

Another object is to provide a fuel supply pump of such construction that it can be quickly adapted for use in either a one pipe or two pipe oil burning system.

Another object is to provide a fuel supply pump of the multi-stage type which is more efficient in operation and of longer life than pumps of corresponding size heretofore known.

Another object is to provide a fuel supply pump for oil burning apparatus of the multi-stage type in which the pumping means of one stage withdraws oil from the source of supply and the pumping means of another stage delivers the oil under pressure to the oil burner, which is of such construction that the oil is supplied under pressure to the second gear set.

Another object is to provide an oil burner fuel supply pump of the multi-stage type in which the primary stage pumping means serves as a booster for the secondary stage pumping means and in which a portion of the load on one pumping means is borne by the other pumping means.

A further object is to provide an oil burner fuel supply pump in which the pump casing is provided with integral strainer and pressure regulating chambers and in which the strainer means is of new and improved construction.

Referring to the accompanying drawings, which illustrate suitable embodiments of the present invention,

Figure 1 is a plan view of the pump, showing the same mounted on a driving motor:

Figure 2 is an end elevation of the pump, a portion of the closure plate being broken away.

Figure 3 is an enlarged longitudinal section of the pump taken approximately on the line 3—3 of Figure 2, showing the detailed construction of the pump interior;

Figure 4 is an enlarged transverse section taken on the line 4—4 of Figure 1, showing the strainer and pressure regulating mechanism in particular;

Figure 5 is a schematic diagram showing the passage of the oil during the pumping operation;

Figure 6 is an enlarged section taken on line 6—6 of Figure 2;

Figure 7 is a transverse section taken on line 7—7 of Figure 6;

Figure 8 is a transverse section taken on line 8—8 of Figure 6;

Figure 9 is a plan view of the upper end of the strainer cap;

Figure 10 is side elevation of the upper end of the strainer cap, a portion of the same being in section;

Figure 11 is a side elevation of the strainer, a portion of the same being in section;

Figure 12 is a fragmentary section corresponding in part to Figure 3, showing a modified construction for use in an oil burner system of the two-pipe type;

Figure 13 is a view like Figure 12 in which the modified construction is reversed for use in a burner system of the one-pipe type, and

Figure 14 is a fragmentary upper plan view of the arrangement shown in Figure 13, a portion 20 of the same being shown in section.

In fuel pumps for oil burning apparatus it is frequently the practice to employ a multiple stage apparatus in which one pumping means is employed to draw the oil from the oil supply tank 25 and a second pumping means is employed to deliver the withdrawn oil to the oil burner nozzle. In such constructions the withdrawn oil is at atmospheric pressure and the pressure of the oil delivered to the oil burner nozzle is produced entirely by the second pumping means.

Briefly, our invention is primarily directed to the provision of an intermediate chamber or passage between the primary and secondary stages in which the oil supplied thereto from the source 35 of supply is placed under a pressure above atmospheric pressure, and in which the pressure is controlled in such manner that it will not exceed a selectable predetermined pressure. In providing for this the primary stage gears or pumping 40 means supplies the oil to this chamber and builds up the pressure therein, and the secondary stage gears or pumping means withdraws this oil which is under pressure and delivers it for supply to the oil burner under a predetermined higher pressure.

Assuming that the oil is to be delivered from the pump to the oil burner nozzle under a predetermined pressure, we have found that by providing a pressure above atmospheric, on the oil 50 intermediate the primary and secondary stages, a portion of the load on the secondary stage pumping means is shifted to the primary stage pumping means with the result that the pump will operate more efficiently and will have longer 55

life than one of the same size not employing an intermediate pressure between the two stages. In this connection, the primary stage pumping means serves as a booster for the secondary stage pumping means.

Our invention is also directed to an improved arrangement of parts, and particularly to an improved means for easily converting the pump for operation in a one-pipe or a two-pipe oil burner system, and to the strainer device for freeing the oil of dirt and sediment, as will hereinafter appear.

Referring to the accompanying drawings in which like numerals refer to like parts throughout the several views, first, describing the pump body, the entire pump is housed within a single body member or casting 20 having a strainer chamber 21, a discharge or pressure regulating chamber 22, a pressure chamber 23 at one end which is closed in by a cover plate 24 secured to the body casting 20 by suitable cap screws 25, and a seal chamber 26 at the opposite end. Referring to Figures 4 and 6, in particular, it is to be noted that the strainer and pressure regulating chambers 21 and 22, respectively, comprise bores having parallel vertical axes arranged at opposite sides of the common horizontal axis of the pressure and seal chambers 23 and 26, respectively, and adjacent the seal chamber 26, thus providing a compact integral arrangement.

The body casting 20 is provided, as shown in Figures 3 and 6, with a bore 27 coaxial with the seal chamber 26 and opening at one end into the seal chamber 26, the opposite end being formed with an eccentrically arranged counter-bore 28. Disposed within the bore 27 is a flanged shaft bushing 29 which is inserted from the seal chamber end of the body casting 20.

The pumping unit, which will now be described, is assembled from the pressure chamber end of the body casting 20, before the cover plate 24 is assembled, and comprises a shaft 30, primary stage gears 31, secondary stage gears 32, a crescent plate 33 and a crescent plate 34.

Referring to Figures 3, 6 and 7, the crescent plate 34 is formed with a closed end bore 35 in the face 36 thereof, which forms a journal for one end of the shaft 30, and with a crescent 37 projecting from the face 36. Fixed to the shaft 30 by means of a key 38 is the gear 32a of the secondary stage gear set 32 which engages with the face 36 and the radially inner face 39 of the crescent 37. The other gear 32b of the gear set 32 is of the internal type, having its teeth meshed with the gear 32a and rotatably engaged with the radially outer face 40 of the crescent 37.

The crescent plate 33 is formed with a laterally extending crescent 41 on its face 42, a shaft bore 43 and with a counter bore 44 in its other face 45. The face 45 seats against the face 36 of the crescent plate 34, with the counter bore 44 surrounding the secondary stage gear 32b in close running engagement. The primary stage gear 31a of the gear set 31 is fixed to the shaft 30 by means of a pin or key 46 and engages with the face 42 and with the radially inner face 47 of the crescent 41, and, similar to the gear 32b, the gear 31b of the primary stage gear set 31 is of the internal type and has running engagement with the radially outer face 48 of the crescent 41.

In the assembly, the shaft 30 extends through the journal 29 and gear 31b is disposed within the counter bore 28 with close running engagement, the face 42 of the plate 33 engaging the face 49 of the body casting. The sub-assembly

just described is secured to this face 49 by suitable cap screws 50 extending through the plates 33 and 34, and, in the assembly, the gears of the two sets have substantially sealed running engagement with the faces of the parts described so as to prevent substantial leakage. During operation the gears 31b and 32b rotate around the gears 31a and 32a respectively. It is to be noted that shaft 30 extends beyond the journal bushing 29 and into the seal chamber 26.

The pump passages, which will now be described, comprise inlets and outlets for each stage. The inlet for the primary stage gear set 31 comprises a passageway 51 (Figure 4) communicating at one end with the upper end of the strainer chamber 21 and at its other end with one end of a passageway 52 (Figures 3 and 4) disposed in the pump body casting above the shaft 30, the axis of the passageway 52 being parallel with the axis of the shaft 30, and opening through the face 49 into communication with a passageway 53 formed in the face 42 of the crescent plate 33 and opening to the primary stage gears 31a and 31b at the left and just above one end of the crescent 41, as shown in Figure 7.

The outlet for the gears 31a and 31b is at the right and just above the other end of the crescent 41 as viewed in Figure 7 and is through a discharge passageway 54 in the face 42 of crescent plate 33, which passageway 54 opens directly through the periphery of the plate 33 into the pressure chamber 23.

The inlet passages for the secondary stage gear set 32 include a passageway 55 formed in the crescent plate 34, opening at one end through the periphery of the plate 34 (Figure 8) to the pressure chamber, and at the other end in a port 56 to the gears 32a and 32b at the left and just above the end of the crescent 37, as viewed in Figure 8.

The outlet passages for the secondary stage gear set 32 include a port 57 opening from the gears 32a and 32b at the right and just above the other end of the crescent 37, as viewed in Figure 8, into a passageway 58 in the plate 34 which terminates in a port 59 that opens into a passageway 60 in the plate 33, which passageway 60 (Figures 3 and 8) opens in turn into a passageway 61 in the body casting 20, the latter passageway being below the shaft 30 and parallel thereto. The passageway 61 communicates with a passageway 62 in the body casting 20 which opens into the pressure regulating chamber 22 near the lower end thereof, as shown in Figure 4.

Referring now to Figures 4, 6, 9, 10, and 11, the strainer chamber 21 is closed at its lower end by a threaded plug 63 having an opening 64 therethrough which is threaded at 65 for the reception of an inlet pipe fitting and inlet pipe 66a, (Figure 2) which leads to the supply tank (not shown), and at 66 with a counter bore to form a sump or well. The strainer proper comprises a relatively deep cup shaped lower end piece 67 preferably in the form of a sheet metal stamping, an upper inverted cup-shaped end piece 68 in the form of a metal stamping, and an endless strainer screen 69 having its open ends fitting within said end pieces 67 and 68. The screen 69, instead of being cylindrical, as is the usual practice, is formed with a plurality of longitudinally extending corrugations or indentations 70, thereby forming a plurality of generally radial screen surfaces 71, as shown in Figure 6. The upper end piece 68 is formed with apertures 72 corresponding in number to the number of indentations 70, and

each aperture is without or exteriorly of the screen 69 and disposed between the adjacent screen surfaces 71 that form one indentation 70. Secured within a central opening in the lower end 5 piece 67 is a vertically rising tube 73 having openings 74, therethrough near its upper end, as shown in Figure 4. As shown in this view, the strainer assembly just described is positioned within the chamber 21 with the end pieces 67 and 68 en- 10 gaging the wall thereof and with the lower end piece resting on the closure plug 63. In this position the upper end piece is slightly below the outlet to the pump inlet passageway 51. A closure plug 75 is threaded into the upper end of the chamber 21 and disposed between the plug 75 and upper end piece 68 is a compression spring 76 which holds the strainer assembly in assembled 15 relation.

When oil is being drawn into the pump, it 20 passes from the well 66 upwardly through the tube 73 and thence outwardly through the openings 74 into the space within the screen 69. The oil then passes through the screen walls 71 and upwardly through the apertures 77 into the space 25 above the end piece 68 from which the pump inlet 51 opens.

The lower end piece 67 forms a sump or settling chamber into which the sediment collects.

In order to clean the strainer, the plug 75 and 30 spring 76 are removed, and the assembly is removed by the use of a suitable hooked instrument, after removal, the parts can be separated and cleaned. In this connection all of the sediment removed from the oil by the screen 69 collects in the sump provided by the cup-shaped lower end piece 67, so that upon removal of the screen, none of the sediment will fall back into the suction line.

Referring now to Figure 4, the lower end of the 40 pressure regulator chamber 22 is closed by a threaded plug 78, there being a gasket 79 of layers of suitable material of variable thickness between the flange of the plug 78 and the body casting. The plug 78 is formed with a threaded 45 aperture 80 for reception of a suitable outlet fitting and outlet pipe 80a (Figure 2) which leads to the oil burner (not shown), and the portion extending into the chamber 22 is counterbored at 81 to receive a valve member 82 having a discharge port 83 therein. The pressure regulating mechanism comprises a tubular member 84 fitted tightly within the chamber 22 and having its lower end slightly above the outlet part of the discharge passageway 62. Reciprocably mounted 50 within the member 84 is a cup-shaped member 85 having at its lower closed end 86 a valve needle 87 for cooperation with the discharge port 83. The valve needle 87 is urged to its port-closing position by a compression spring 88 having one 55 end within the cup-shaped member 85 and its opposite end engaged with an abutment flange 89 formed on a screw member 90 which is threadably carried by a closure plug 91 that is threaded into the upper end of the chamber 22. The upper 60 end of the screw member 90 projects into a counterbore 92 formed in the upper side of the plug 91. In order to conceal this end of the screw member, a threaded closure element 93 is provided to close the counterbore 92. It is apparent that by adjusting the screw 90 that needle 65 87 can be made to move from its seat at any desired pressure.

It is preferable to limit the pressure at which the oil passes through the discharge port 83, 70 and in order to provide for this, a relief passage

94 is provided in the bore of the sleeve 84 and openings 95 are provided through the cylindrical wall of the cup-shaped member 85. In operation, the pressure of the oil within the space between the closed end 86 and valve plate 82 causes the member 85 to slide in the sleeve 84 and lift the needle to open the port 83. As the pressure increases, the member 85 slides upwardly within the sleeve 84 against the compression of spring 88, and when a predetermined pressure is reached 10 the closed end 86 of member 85 clears the relief passage 94 so that the excess oil will pass through the passage 94 and the openings 95 into the space within the sleeve 84 and above the sleeve. Thus, the action of the pressure of the oil below the 15 member 85 and the counter-acting pressure of the spring 88 together with the relief passage 94 allows only a predetermined pressure on the oil flowing through port 83 to be reached.

A relief passage 96 is provided in the body casting 20 which opens into the space adjacent the upper closure plug 91 for the regulating chamber 22, and which communicates as shown in Figure 6 with a pressure relief chamber 97 (Figures 3, 4, 6 and 7). While adjustment of the regulating 25 valve mechanism is obtained by means of the screw 90, adjustment for the cut off differential is obtainable by removing desired thicknesses of the laminated gasket 79 to vary the position of the valve member 30 32.

With respect to the pressure chamber 23 and with reference to Figure 3, it has been previously described that the primary stage pumping means 31 pumps oil into the pressure chamber 23 and that the secondary stage pumping means 32 35 pumps oil from this chamber. In accordance with the present invention a pressure is maintained so that the secondary stage gear set 32 draws the oil from a zone which is under a pressure above atmospheric. This is accomplished 40 by providing the pressure chamber with a relief valve mechanism so that a predetermined pressure will be maintained therein but which will not exceed a desired maximum. In this connection the body casting is provided with an opening 98 45 which opens into the pressure chamber, the opening being counter-bored at 99 to provide a valve chamber and communicating with the counter-bore 99 and the pressure relief chamber 97 is a passageway 100. The bottom of the counter-bore 50 99 is tapered to form a valve seat 101, surrounding the end of opening 98, for engagement therewith of a valve ball 102. The ball 102 is urged to closed position by a compression spring 103 which is held in compression by a cap 104 55 threaded into the counter-bore 99. The gasket 105 for the cap 104 is of the laminated variable thickness shim type so that the spring may be adjusted for the desired compression whereby to predetermine the pressure at which the valve 60 102 will move from its seat 101 and permit oil to flow into the pressure relief chamber 97 when the predetermined pressure in chamber 23 is reached. By removing different thicknesses of the gasket material 105 the desired compression 65 may be placed in the spring 103.

It is the practice in some oil burner installations to employ what is commonly known as a two pipe system or a one pipe system. In two pipe systems, the excess or by-pass oil is returned through a pipe to the storage tank, and in one pipe systems the excess oil is returned to the suction side of the pump. The fuel supply device of the present invention is arranged to be used with either a two pipe system or a one pipe 70 75

- system by merely opening one passageway and closing another. We have shown variations of this arrangement in the drawings. In the construction shown in Figures 3 and 7, it is to be noted that the pressure relief chamber 97 extends around one side of the pump body casting from the top to the bottom thereof and that this chamber opens through the bottom of the casting in a threaded port 106 which is closed by a plug 107. It is also to be noted that the relief chamber 97 at the upper side of the pump body casting is formed with a lateral extension 108. This extension connects with the intake passageway 52 (Figure 3) through a vertical passage 109. When the pump is used in a one pipe system, the closure plug 107 is left in place and the excess or by-pass oil from the pressure chamber 23 and the pressure regulating chamber 22 which passes into the relief chamber 97 returns to the suction side of the primary stage pumping means through the passage 109. When, however, the pump is used in a two pipe system, the closure plug 107 is removed and a pipe (not shown) leading to the fuel supply tank (not shown) is connected to the threaded port 106 in its place, and the passage 109 closed, in which case the excess or by-pass oil flows from the relief chamber 97 through the return pipe described to the fuel supply tank.
- In Figure 3, the closure means for the passage 109 under the condition described comprises a valve needle 110 mounted on or forming a part of a screw element 111 threaded in an opening 112 through the body casting 20, which opening 112 is coaxial with the passage 109 and which may be closed by a closure plug 113. By threading the screw element 111 downwardly the tapered valve needle 110 will enter and close the passage 109.
- In the modified construction of Figures 12, 13 and 14 the passage 109 is not connected into the relief chamber 97, as in Figure 3, but in this case, it extends and opens out through the body casting 20 and a similar passage 114 is provided adjacent the passage 109, which opens into the relief chamber 97. When the two pipe system is used these two passages 109 and 114 are closed by means of a gasket 115 which is tightly held in position by the solid surface of a member 116 that is secured to the body casting by a screw 117, the solid surface of the gasket and the one side face of the member 116 sealing and closing off these passages as shown in Figure 12.
- The member 116 has an annular groove 118 in its opposite side face and the gasket 115 has openings 119 therein spaced the same as the passages 109 and 114, so that when the pump is to be used in a one-pipe system, it is only necessary for the installation man to align the gaskets 119 with the passages 109 and 114 and mount the member 116 in place with the grooved side in engagement with the gasket 115, as shown in Figure 13. In this case the excess or by-pass oil will flow from the chamber 97 through passage 114 to the groove 118 and thence through passage 109 to the pump inlet passageway 52. It is obvious that other well known means for closing and/or connecting the passages 109 and 114 may be provided.
- With further reference to Figure 3, a suitable seal is provided for the shaft 30, which comprises a bearing plate 120 engaged with the end of bushing 29, a second annular member 121 pressed on the shaft which engages plate 120 and a shouldered non-rotatable collar 122 closely sur-

rounding the shaft 30 and having end thrust engagement with the member 121. Mounted between the collar 122 and a washer-like member 123 carried on the collar 122 is a flexible disk 124 of suitable oil sealing material which seats on a shoulder 125 formed in the seal chamber 26. The flexible disk 124 is securely clamped between the washer 123 and collar 122 and against the shoulder 125 by means of a cup-shaped element 126 having its peripheral edge engaged with the peripheral portion of the disk 124, between which member 126 and the washer 123 there is a spring 127 under compression. A plate 128 surrounding the shaft 30 is secured to the body casting by screws 129 and abuts the element 126 to clamp the flexible disk 124 between shoulder 125 and element 126 and to compress the spring 127 to thereby clamp the disk 124 between the washer 123 and collar 122.

A running seal is thus provided which prevents leakage of oil from the seal chamber 26 which might leak thereto from the shaft bearing.

As shown in Figure 6, a passage 130 is preferably provided between the seal chamber 26 and strainer chamber 21 so that the suction will draw excess oil from the seal chamber 26.

Suitable mounting flanges 131 may be provided on the body casting 20 for mounting the pump on a motor 132, shown in Figure 1, the motor and pump shafts having suitable interlocking parts to provide a drive connection.

If desired, the body casting 20 may, as shown in Figure 3, be provided with a passage 133 leading to the discharge passage 61 so that a gage (not shown) may be attached thereto to determine the pressure being produced. This passage 133 is normally closed by a closure plug 134.

In order to more clearly show the passage of oil through the fuel supply device described and in order to more clearly set forth the operation of the device, a schematic arrangement of the parts and passages is shown in Figure 5. Referring now to Figure 5, and bearing in mind that the primary stage and secondary stage gear sets are driven by the same shaft, and assuming that the device is in operation, the primary stage gear set, of course, creates a suction with the result that oil is withdrawn from the fuel supply tank through pipe 65a. This oil is drawn upwardly through the pipe 73 within the strainer chamber 21 and strainer screen 69, passes through the strainer screen 69 and thence through passageways 51, 52 and 53 and the inlet port A. The oil is discharged under pressure through the discharge port B and the outlet passage 54 into the pressure chamber 23 wherein a predetermined pressure is created. The secondary stage gear set 32 likewise creates a suction and the oil in chamber 23, which is under pressure, is withdrawn through the intake passage 55 and intake port C. The oil is discharged under pressure through the discharge port D and thence through passageways 60, 61 and 62 into the pressure regulating chamber 22 for discharge through the controlled discharge port 83 to the pipe 80a which leads to the oil burner nozzle, the pressure of the oil causing member 86 to lift needle 87 from the seat. Should the pressure of the oil exceed a predetermined maximum, the excess pressure raises the member 86 to clear the edge of the by-pass passage 94 and a portion of the oil passes through the by-pass 94, rises in chamber 22 and flows through passageway 96 to the relief or by-pass chamber 75.

97. The spring 88 and attendant valve mechanism in the regulating chamber 22 thus functions to maintain a predetermined pressure on the oil flowing through the outlet port 83 to the oil burner and to by-pass oil whenever the oil pressure tends to exceed the predetermined pressure.

Also, the pressure of the oil in the pressure chamber 23 is limited to a predetermined value, and should the pressure tend to increase beyond this value the ball 102 opens the port 98 to by-pass oil through passage 100 to the relief or by-pass chamber 97.

The oil in the by-pass chamber 97 in a one-pipe system, such as shown in Figure 5, flows, due to suction pressure, through passageway 109, the valve needle 110 being away from its seat under this condition, and thence through inlet passageways 52 and 53 to the suction side of the primary stage gear set 31 for recirculation. If, however, the system is a two pipe system, the passageway 109 is closed by the valve needle 110, and a pipe (not shown) leading to the fuel supply tank is connected to the outlet 106 in lieu of the closure plug 107, and under such condition, the oil in the by-pass chamber 97 drains by means of such pipe back to the fuel supply tank.

By providing a pressure chamber intermediate the gear sets 31 and 32 in which the pressure is controlled, a more efficiently operating fuel supply device for oil burners is provided in that a portion of the load, i. e., the creation of the discharge pressure is borne by the primary stage gear set, thus relieving the secondary stage gear set of the burden of all the load. The load is thus distributed between the two gear sets with the result that there is greater efficiency and economy of operation and the life of secondary gear set is prolonged.

Various other advantages result from the fuel supply device of the present invention. The arrangement is compact and neat appearing and the parts are so arranged as to provide for easy and rapid assembly. Also a new and advantageous arrangement is provided for freeing the oil of dirt and sediment before it enters the pump gears.

Another advantageous feature is that various passages for the gears are so arranged that the gears will remain wetted to provide for self-priming.

While preferred embodiments of the invention have been illustrated and described, it is to be understood that various changes may be made in the detailed construction and arrangement of the parts without departing from the spirit and scope of the appended claims.

What we claim is:

60 1. A fuel supply pump for oil burners and the like comprising a pump body having a pressure chamber therein, primary stage pumping means carried by said body, inlet and outlet passages for said means, said outlet passage opening into said chamber, a secondary stage pumping means carried by said body, inlet and outlet passages for said secondary stage pumping means, said last named inlet passage opening from said chamber, a return by-pass leading from said chamber, said last named outlet passage terminating in a discharge chamber, pressure regulating means associated with said discharge chamber for maintaining a predetermined pressure therein, a return passage for said discharge chamber for bypassing oil therefrom when the pressure therein exceeds a predetermined maximum, a pressure relief valve associated with said pressure chamber for by-passing oil to said first mentioned return by-pass from said pressure chamber when the pressure therein exceeds a predetermined maximum, and a by-pass chamber in said body said return passage and return by-pass being independent of each other and communicating with said by-pass chamber whereby oil from said return by-pass enters said by-pass chamber independently of said pressure chamber, said body having a passageway therein communicating with said by-pass chamber and the first mentioned inlet passage.

65 pressure therein exceeds a predetermined maximum, a pressure relief valve associated with said pressure chamber for by-passing oil to said first mentioned return by-pass from said pressure chamber when the pressure therein exceeds a predetermined maximum, and a by-pass chamber in said body, said return passage and return by-pass being independent of each other and communicating with said by-pass chamber whereby oil from said return by-pass enters said by-pass chamber independently of said pressure chamber.

70 2. A fuel supply pump for oil burners and the like comprising a pump body having a pressure chamber therein, primary stage pumping means carried by said body, inlet and outlet passages for said means, said outlet passage opening into said chamber, a secondary stage pumping means carried by said body, inlet and outlet passages for said secondary stage pumping means, said last named inlet passage opening from said chamber, a return by-pass leading from said chamber, said last named outlet passage terminating in a discharge chamber, pressure regulating means associated with said discharge chamber for maintaining a predetermined pressure therein, a return passage for said discharge chamber for bypassing oil therefrom when the pressure therein exceeds a predetermined maximum, a pressure relief valve associated with said pressure chamber for by-passing oil to said first mentioned return by-pass from said pressure chamber when the pressure therein exceeds a predetermined maximum, and a by-pass chamber in said body said return passage and return by-pass being independent of each other and communicating with said by-pass chamber whereby oil from said return by-pass enters said by-pass chamber independently of said pressure chamber, said body having a passageway therein communicating with said by-pass chamber and the first mentioned inlet passage.

75 3. A fuel supply pump for oil burners and the like comprising a pump body having a pressure chamber therein, primary stage pumping means carried by said body, inlet and outlet passages for said means, said outlet passage opening into said chamber, a secondary stage pumping means carried by said body, inlet and outlet passages for said secondary stage pumping means, said last named inlet passage opening from said chamber, a return by-pass leading from said chamber, said last named outlet passage terminating in a discharge chamber, pressure regulating means associated with said discharge chamber for maintaining a predetermined pressure therein, a return passage for said discharge chamber for bypassing oil therefrom when the pressure therein exceeds a predetermined maximum, a pressure relief valve associated with said pressure chamber for by-passing oil to said first mentioned return by-pass from said pressure chamber when the pressure therein exceeds a predetermined maximum, and a by-pass chamber in said body said return passage and return by-pass being independent of each other and communicating with said by-pass chamber whereby oil from said return by-pass enters said by-pass chamber independently of said pressure chamber, said body having a passageway therein communicating with said by-pass chamber and the first mentioned inlet passage, and manual means for closing said last named passageway.

80 4. In an oil supply pump for oil burners and the like, a body casting closed at one end and open

at the opposite end to provide a chamber, said closed end having a shaft bore in alignment with said open end, said body casting having a strainer chamber and a regulating chamber
5 therein, a pumping unit, said pumping unit comprising plate members, a primary stage gear set and a secondary stage gear set carried by said plate members, a common drive shaft for said gear sets and inlet and outlet passages in said 10 plate members for each of said gear sets, said pumping unit being insertable through said open end as a unitary structure, means for securing said unit to said closed end with said shaft extending through said bore, the outlet passage of 15 said primary stage gear set and the inlet passage of said secondary stage gear set opening into said first mentioned chamber, a passageway in said body casting between said strainer chamber and the inlet passage of said primary gear set, a passageway in said body casting between the outlet 20 passage of said secondary gear set and said regulating chamber, and closure means for said open end.

5. A fuel supply pump for oil burners and the like comprising a body member having a strainer chamber, a regulating chamber and a pressure chamber, primary pumping means within said body member connected with said strainer chamber for delivering oil to said pressure chamber, 25 secondary pumping means for drawing oil from said pressure chamber and delivering same to said regulating chamber, said body member having a return oil passage, a pressure relief means associated with said pressure chamber for limiting the pressure therein and to deliver excess oil 30 to said return oil passage, said regulating chamber having a return port connected with said return oil passage and a main outlet port, and pressure regulating means in said regulating 35 chamber and associated with said return port and main outlet port for delivering oil through said outlet port at a predetermined pressure and for delivering excess oil through said return port to said return passage independently of said 40 pressure chamber when the pressure exceeds said pressure chamber when the pressure exceeds said 45 predetermined pressure.

6. In a fuel supply pump for oil burners and the like, a pump body having an inlet passageway and a pressure regulating chamber, pumping 50 means within said body connected with said inlet passageway for pumping oil to said regulating chamber, a by-pass chamber having a pair of outlet ports opening through said body, said body having a return passage between said by-pass 55 chamber and said pressure regulating chamber, said body having a third port opening therethrough and communicating with said inlet passage, said third port being relatively close to one of said outlet ports, a reversible member secured 60 to said body over said one port and said third port and having a passageway therein for con-

necting said last mentioned ports in one position and closing said ports in another position, and removable closure means for the other of said first mentioned ports.

7. In a fuel supply pump for oil burners and the like, a pump body having an inlet passageway and a pressure regulating chamber, pumping means within said body connected with said inlet passageway for delivering oil to said regulating chamber, a by-pass chamber, a by-pass passageway between said regulating chamber and said by-pass chamber, a passageway between said by-pass chamber and said inlet passageway, a port in said body opening to said by-pass chamber, a closure plug for said port, said by-pass passageway having a valve seat therein and a screw member threaded through said body and having a valve member thereon adapted to cooperate with said valve seat to close said by-pass passageway, said screw member being accessible 20 from without said body.

8. A fuel supply pump for oil burners and the like comprising a housing member having a pressure chamber therein, primary stage pumping means carried by said body, inlet and outlet passages for said means, said outlet passage opening into said chamber, a secondary stage pumping means carried by said body, inlet and outlet passages for said secondary stage pumping means, said last named inlet passage opening from said chamber, a return by-pass leading from said chamber, and a pressure relief means normally closing said by-pass for limiting the pressure in said chamber and for by-passing oil from said chamber when the pressure therein exceeds said predetermined maximum, said pressure relief means including a valve member for opening and closing said by-pass, spring means urging said valve member to closed position, and a screw member accessible from without said housing member and engaging said spring means for varying at will the pressure exerted by said spring means on said valve member.

9. In a fuel supply pump for oil burners and the like, a pump body having an inlet passageway and a pressure regulating chamber, pumping means within said body connected with said inlet passageway for pumping oil to said regulating chamber, a by-pass chamber having a pair of outlet ports opening through said body, said body having a return passage between said by-pass chamber and said pressure regulating chamber, said body having a third port opening therethrough and communicating with said inlet passage, said third port being relatively close to one of said outlet ports, a member secured to said body and having a passageway therein connecting said one port and said third port, and closure means for the other of said first mentioned ports.
